UNITED STATES PATENT OFFICE.

WILLIAM W. MULLENDORE, OF KNOXVILLE, TENNESSEE.

WINDOW SHADE AND CURTAIN HANGER.

Application filed June 14, 1926. Serial No. 115,909.

This invention relates to window shade and curtain hangers and aims to provide a novel hanger of this character which may be readily and easily secured to a window frame, eliminating the necessity of using screws, nails or the like, to secure the hanger, thereby avoiding marring the window frame.

Another object of the invention is to provide a hanger which may be adjusted for use in connection with window frames of various widths, novel means being provided for securing the hanger in position by its contact with the outer side edges of the window frame.

A still further object of the invention is to provide an adjustable curtain hanger having means to permit it to be readily snapped onto the main or body portion of the hanger.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings

Figure 1 is a top plan view of a combined curtain and shade hanger.

Figure 2 is a front elevational view thereof.

Figure 3 is a sectional view taken on line 3—3 of Figure 2.

Figure 4 is a rear elevational view of the device.

Figure 5 is a sectional view taken on line 5—5 of Figure 2.

Figure 6 is an end elevational view of the hanger.

Figure 7 is a perspective view illustrating the supporting members at the ends of the hanger.

Referring to the drawings in detail, the device includes a main supporting section indicated generally by the reference character 5 formed preferably of sheet metal, the side edges thereof being bent inwardly as at 6 to provide a guideway for the movable section 7, which is also formed of a length of sheet metal, the side edges thereof being bent inwardly to underlie the inturned side edges of the main supporting section 6.

At one end of the main supporting section 6, is an end section 8 that is secured to

the section 6 by means of the rivets 9', the inner end of the section 8 acting as a stop against which the inner end of the section 7 abuts, to restrict the inward movement of 60 the section 7.

Mounted within the sections 7 and 8 and secured in position by bending the outer portions of the flanges or inturned side edges of the members 7 and 8, downwardly, are securing members 9 and 10 respectively, each of which embodies a rod bent intermediate its ends to provide parallel leg portions 11, the free ends thereof being bent rearwardly and sharpened to provide spurs 12 designed 70 to embed themselves in the outer side edges of the window frame to which the device is to be secured.

The reference character 13 indicates a coiled spring that has its ends secured to 75 the members 9 and 10 as clearly shown by Figure 4 of the drawings so that the spring will normally urge the members 9 and 10 towards each other to force the spurs 12 into the frame of the window.

The curtain support includes telescoping sections 14 and 15, each of which has inwardly extended portions 16, and overlying flanges 18 which overlying flanges are designed to be bent downwardly against the 80 securing members 19 which also include rods bent intermediate their ends and formed with hook members 20 at their ends to be hooked over the leg portions 11 of the securing members 9 and 10, the members 19 being 85 however bent to provide right angled portions 21 so that the curtain support will be held in spaced relation with the main supporting member.

As shown by Figure 6 of the drawings one 90 of the hook members 20 is shorter than the other hook member, to the end that the long hook member may be positioned over the leg members of the securing member, and the opposite hook member snapped into 100 position.

Thus it will be seen that due to this construction, the curtain hanger may be adjusted laterally when the main supporting member has been adjusted for a predetermined window frame construction.

Shade brackets indicated at 22 are formed by bending a length of resilient metal intermediate its ends to provide openings 23 for the pintle of a window shade, one end of the bracket being substantially long to provide a finger 24 extended below the main sup-

porting section so that by pressing the finger inwardly or towards the curtain support the shade brackets may be readily released.

5 Thus it will be seen that by pulling the sections of the main supporting member apart and positioning the same adjacent to a window frame, the spurs of the securing members will be drawn into the edges of the 10 window frame by the spring 13 to secure the device in position.

I claim:

An end member for combined window shade and curtain hangers embodying a

main section formed of a length of wire 15 bent intermediate its ends defining parallel leg members, spurs formed at the ends of the parallel leg members, an auxiliary section including a length of wire bent intermediate its ends and defining leg members, 20 the last mentioned leg members having right angled portions terminating in inwardly extended hooks to grip the leg members of the main section, and supporting members to which the leg members are secured.

In testimony that I claim the foregoing as my own, I have hereto affixed my signature.

WILLIAM W. MULLENDORE.
